UNITED STATES PATENT OFFICE.

JAMES P. BOFSEN, OF HOBOKEN, NEW JERSEY.

DESIGN FOR GIMP.

SPECIFICATION forming part of Design No. 16,552, dated March 2, 1886.

Application filed December 7, 1885. Serial No. 185,000. Term of patent 7 years.

To all whom it may concern:

Be it known that I, JAMES P. BOESEN, of Hoboken, county of Hudson, and State of New Jersey, have invented a new and original Design for Gimp, of which the following is a specification.

My design for gimp consists of a band running centrally of the body of the gimp in direction of its length, ornamented by bars having reversely-bent ends and with their bodies diagonally crossing said band, said bars representing continuous screw threads about or around the longitudinal central band, with their bent ends overlapping opposite sides of said band. The effect also is increased by so arranging the central longitudinal band on the body of the gimp—that is, between the opposite exposed border portions thereof—as that it will present a raised appearance. The diagonal bars with their reversely-bent ends are of step shape throughout their length, representing a series of rectangular blocks.

Reference is to be had to the accompanying

drawing, which forms a part of this specification, and which represents a longitudinal face view of a piece of gimp having my design.

b indicates the central longitudinal band, *c* the exposed border sides of the body, and *d* the transverse diagonal bars having reversely-bent ends.

I claim—

The design for gimp herein shown and described, the same consisting of a body having a central longitudinal band ornamented by bars *d*, having reversely-bent ends overlapping the sides of said band within or on the exposed border portions *c* of the gimp, and having their bodies cross diagonally the band *b*, said bars representing continuous screw-threads composed of rectangular blocks upon the body of the gimp about or around the band *b*.

JAMES P. BOESEN.
